METHOD AND APPARATUS FOR SHAPING TUBING

Application filed January 12, 1931. Serial No. 508,113.

This invention relates to a method and apparatus to be used in changing the cross section of hollow metal tubing. The invention is particularly applicable for use with metal tubing having a longitudinal seam, the edges of which are welded or brazed or otherwise secured together. When an attempt is made to flatten such a piece of tubing or to change it to elliptical or oval cross section, the welded edges frequently separate with a hinge-like action about the outer edge of the weld.

It is the object of our invention to provide a method and apparatus for changing the cross section of metal tubing in such manner that the portion of tubing adjacent the longitudinal weld shall retain substantially its original contour, while distortion of the tubing from its original contour occurs entirely in continuous metal removed from the seam or joint.

A more specific object of our invention is to provide dies for such purposes which engage the tubing along spaced parallel longitudinal lines or edges only.

Our invention further relates to details of construction and operation which will be hereinafter described and more particularly pointed out in the appended claims.

Apparatus suitable for carrying out our improved method is shown in the drawing, in which

Fig. 1 is a plan view of a piece of tubing of circular cross section;

Fig. 2 is a sectional elevation of a pair of dies engaging the circular tubing;

Fig. 3 is a similar view but showing the position of the parts after the operation of the dies is completed;

Fig. 4 is a view similar to Fig. 1 but showing the tubing after the change in cross section;

Fig. 5 is a sectional elevation showing dies for producing a tubing of semi-oval section;

Fig. 6 indicates the production of a fully flattened tubing from the product shown in Fig. 4 or Fig. 5, and

Fig. 7 indicates the difficulty heretofore encountered in carrying out this press operation.

It has been the usual procedure in flattening tubing or changing its section, to provide a pair of dies 10 and 11 (Fig. 7) having continuous concave work-engaging surfaces. When such dies engaged a piece of tubing along a longitudinal seam, the pressure of the dies against the welded portion frequently caused the parts to separate and bend inward along the seam, as indicated in Fig. 7, deforming the tubing and opening a longitudinal crack therein.

In our improved method of operation, we avoid the defects of the former procedure by providing dies 20 and 21 having spaced parallel edge portions 22 separated by a deep recess 23. The edges 22 engage the tube T along lines relatively remote from the seam or weld W and we thus transform the tube T to the substantially oval or elliptical section indicated at T' in Fig. 3, without substantially changing the shape of the tube in those portions lying over the recess 23 and between the parallel edges 22 of the dies 20 and 21.

Consequently there is no substantial tendency to open the weld W and there is no hinge action about the joint such as occurred when using the old style dies indicated in Fig. 7. Consequently a welded tube may be readily transformed to a flattened elliptical or oval cross section without opening or weakening the longitudinal weld or seam therein.

This is an important advance in the art of using welded or brazed tubing, as it permits the use of such tubing in many places where a seamless tubing was heretofore required. Such seamless tubing is very much more expensive than welded or brazed tubing and in many places the cost is prohibitive.

In Fig. 5, we show the application of our invention to the production of a tubing T² of semi-oval cross section by the use of a single recessed die 30 only, the other die 31 being flat. It will be understood that the blank tubing is positioned so that the weld or seam will be located in the recess of the die 30 as the pressure thereof is applied to the tubing.

The tubing T' or T² produced as shown in Figs. 3 or 5 may be thereafter transformed to the fully flattened tubing T³ shown in Fig. 6

by the use of a pair of flat dies 40 and 41, which have much less tendency to open the seams in this case than they would have if applied direct to the round tubing T.

5 Having thus described our invention and the manner in which it may be practiced, we do not wish to be limited to the details herein disclosed, otherwise than as set forth in the claims, but what we claim is:—

- 10 1. The method of changing the cross section of circular tubing which consists in applying pressure along two spaced parallel lines at one side of the tubing and in a direction substantially perpendicular to the plane of said parallel lines, such pressure being resisted along two spaced and opposed parallel lines at the opposite side of the tubing, the tubing being free from direct pressure between the first two lines and also between the last two lines.
- 15 2. The method of changing the cross section of circular tubing which consists in applying pressure along two spaced parallel lines at one side of the tubing and in a direction substantially perpendicular to the plane of said parallel lines, and in opposing the pressure on the other side of said tubing, the tubing being free from direct pressure between said parallel lines.
- 20 3. Apparatus for use in changing the cross section of circular tubing to a substantially elliptical cross section which comprises a pair of dies, each having two parallel angular tube-engaging edge portions substantially spaced apart by an intervening recessed non-engaging portion, the tube-engaging portions of said dies being positioned directly opposite to each other, and the recessed portions of said dies also being positioned directly opposite to each other when said dies are applied to a tube.
- 25 4. The method of changing the cross section of circular tubing which consists in applying pressure along two spaced parallel lines at one side of the tubing and in a direction substantially perpendicular to the plane of said parallel lines, such pressure being resisted along two spaced and opposed parallel lines at the opposite side of the tubing, the tubing being free from direct pressure between the first two lines and also between the last two lines.
- 30 5. The method of changing the cross section of circular tubing which consists in applying pressure along two spaced parallel lines at one side of the tubing and in a direction substantially perpendicular to the plane of said parallel lines, and in opposing the pressure on the other side of said tubing, the tubing being free from direct pressure between said parallel lines.
- 35 6. The method of changing the cross section of circular tubing which consists in applying pressure along two spaced parallel lines at one side of the tubing and in a direction substantially perpendicular to the plane of said parallel lines, such pressure being resisted along two spaced and opposed parallel lines at the opposite side of the tubing, the tubing being free from direct pressure between the first two lines and also between the last two lines.
- 40 7. The method of changing the cross section of circular tubing which consists in applying pressure along two spaced parallel lines at one side of the tubing and in a direction substantially perpendicular to the plane of said parallel lines, and in opposing the pressure on the other side of said tubing, the tubing being free from direct pressure between said parallel lines.

In testimony whereof we have hereunto affixed our signatures.

OTTO W. SIEBERT.
CARL J. BJORSON.
